UNITED STATES PATENT OFFICE.

HENRY W. WINTER, DECEASED, LATE OF METHUEN, MASSACHUSETTS, BY MILLIE E. ADAMS, ADMINISTRATRIX, OF METHUEN, MASSACHUSETTS, ASSIGNOR TO UNITED SHOE MACHINERY CORPORATION, OF PATERSON, NEW JERSEY, A CORPORATION OF NEW JERSEY.

SPLITTING MACHINE.

Specification of Letters Patent.

Patented Nov. 11, 1919.

1,321,176.

Application filed April 11, 1916.

Serial No. 227,980.

To all whom it may concern:

Be it known that HENRY W. WINTER, deceased, late of Methuen, in the county of Essex and State of Massachusetts, invented certain Improvements in Splitting Machines, of which the following description, in connection with the accompanying drawings, is a specification, like reference characters on the drawings indicating like parts in the several figures.

This invention relates to cutting machines and is herein illustrated as embodied in a machine for producing rands and welts, for skiving taps, and for preparing various articles for use in the manufacture of boots and shoes.

In splitting a strip of stock diagonally from corner to corner to produce rands or in splitting such a strip diagonally by a cut extending from a predetermined distance from one corner to an equal distance from the diagonally opposite corner to produce welts, machines have been employed in which the strip is forced against an inclined knife by two rolls, the axis of one roll being fixed and the axis of the other roll movable toward and from the fixed axis of the first-named roll; and, in order to vary the inclination of the knife automatically in accordance with the extent of separation of the rolls, the knife has been connected with the bodily movable roll in such manner that the inclination of the knife increases and decreases with the rise and fall of the movable roll.

According to one feature of the present invention the feed rolls or members are connected in such manner that they are compelled to move equally in opposite directions in response to variations in the thickness of the stock, the inclination of the knife being controlled automatically by the extent of separation of the feed members. With this construction the axis about which the knife turns may be located to coincide with the longitudinal center line of the strip of stock, so that the two beveled rands or welts produced will be equal in cross section at corresponding points irrespective of variations in the original thickness of the strip.

In prior machines of this general type the

edge of the splitting knife has been located close to the bite of the feed rolls so as to guard against buckling of the stock between the rolls and the knife. This construction has the disadvantage that with it only a limited extent of angular movement of the knife is possible owing to the proximity of the knife to the feed rolls. In order to overcome this difficulty, another feature of the invention comprises means for guiding the stock from the feed rolls to the knife. In the illustrative machine two flat faced members engage the stock, one above and the other beneath, and guide it to the knife which is located at some distance from the feed rolls and may readily be adjusted to any angular position. This construction is particularly useful in skiving taps since on such work it is frequently desirable to produce a short, sharply pitched scarf.

Another feature of the invention relates to auxiliary feeding means for feeding the rear portion of the stock to the knife. In the illustrative machine, a continuously reciprocated feed member is held beneath the stock during its feed movement until the rear end of the stock passes said member, whereupon the member rises into operative position and completes the feeding movement.

These and other features of the invention, including certain details of construction and combinations of parts, will be described as embodied in an illustrative machine and pointed out in the appended claims.

Referring to the accompanying drawings,

Figure 1 is a plan of a machine in which the present invention is embodied;

Fig. 2 is a side elevation, certain parts having been broken away;

Fig. 3 is a detail principally in elevation showing the location and support of the member which feeds the rear end of the strip to the splitting knife;

Fig. 4 is a rear elevation, part of the casing having been broken away;

Fig. 5 is a section on the line 5-5 of Fig. 2;

Fig. 6 is a section on the line 6-6 of Fig. 2;

Fig. 7 is a perspective showing the stripping knife and the splitting knife operating upon a piece of stock, and

Fig. 8 is a perspective of the knife holder 5 and knife.

The illustrative machine is similar in its mode of operation to that of the machine of Patent No. 1,025,556, granted May 7, 1912. A sheet of stock 100 such as leather is fed 10 by an upper feed roll 9 and a lower feed roll 11 to a knife 13 which cuts a strip from the sheet and to an inclined knife 15 which splits the strip on an angle. The cut of the knife 15 may extend diagonally from 15 corner to corner of the strip to form two rands, or, as shown in Fig. 7, diagonally from a point spaced from the upper right-hand corner to a point similarly located with respect to the lower left-hand corner to 20 form two McKay welts.

The shaft 17 of the upper feed roll is mounted in a bearing which is carried by arms 20, 21, the hubs at the ends of the arms remote from the bearing being fast to a rock 25 shaft 25; and the shaft 19 of the lower feed roll is similarly carried by arms 22, 23 the remote ends of which are loose upon a rotary shaft 27. An arm 31, which is integral with the hub of the arms 22, 23, has rack 30 teeth at its upper end which mesh with similar teeth formed on the lower end of an arm 29, said latter arm being fast to the rock shaft 25. A spring, not shown, connects the arms 20 and 22 and continually urges them toward each other, the limit of approach of the arms, and consequently of the feed rolls, being determined by stops of any suitable form. When the rolls are separated or caused to approach each other, the 40 extent of their movements is thus equal, the purpose of this construction being to maintain the center of the forward end of the strip of stock in line with the axis of angular movement of the splitting knife irrespective of variations in thickness of the stock, as will presently be described more in detail.

The lower feed roll is driven directly from a large gear 37 on the driving shaft 39 which 50 meshes with a gear 41 on the shaft of the lower feed roll. The upper feed roll is driven from the lower feed roll by floating gears 43, 45 which mesh respectively with a gear 49 on the shaft 19 and with a gear 47 on the shaft 17 as well as with each other. The shafts of the floating gears 43, 45 are connected with each other by links 51 and respectively with the shafts 19 and 17 by links 53, 55. With this construction the 55 separation of the rolls 9 and 11 does not disturb the mesh of the driving gears.

The stripping knife 13 is adjustably clamped in a split holder by a pinch-bolt 57. The splitting knife is slidably mounted in 65 a cylindrical holder 59, the beveled sides of

the knife being received in diametrically opposite V-shaped grooves in the holder. The longitudinal position of the knife in the holder is determined by a back stop in the form of an arm 61 having a conical forward end which is received in a groove in the rear end of the knife, the hub of said arm being mounted upon a rod 63 and being engaged by a thumb-nut 65 threaded on said rod. The pressure of the work against the edge of the knife holds the knife against the stop, said stop being adjustable by means of the thumb-nut 65 to determine the longitudinal position of the knife. The axis of angular movement of the knife passes 70 through the point of the back stop 61 and coincides with the axis of the cylindrical knife holder 59 said holder being angularly movable in a stationary cylindrical carrier 67 having a slot 69 in the stem thereof to 75 receive a screw bolt 71 by which it is adjustably fastened in vertical position to the frame of the machine. It should be particularly noted that the axis of angular movement of the splitting knife 15 passes 80 midway between the feed rolls and is located in a vertical plane which intersects the feed rolls midway between their ends. In other words, when a sheet of stock is placed with its edge against the gage 73 thereby cutting 85 off a strip the width of which is equal to the distance between the gage and the stripping knife 13, the axis of angular movement of the splitting knife 15 passes longitudinally 90 through the center of the strip. The purpose of this construction, as will presently appear, is to cause a strip of given width to be divided into two beveled strips of equal cross-section at all corresponding points 95 irrespective of variations in the thickness of 100 the original strip.

In order to cause angular movement of the splitting knife to take place in accordance with the extent of separation of the feed rolls, and consequently in accordance 110 with the thickness of the stock at the point at which it is being split at any time, a yoke 75, clamped to the knife holder 59, is provided with teeth which mesh with similar teeth formed on one end of the horizontal 115 arm of a bell-crank lever 81, pivoted to the frame of the machine at 83 and having at the upper end of its vertical arm a roll 85. This roll is received in a slot 87 formed in a disk 89 which is fastened to the bearing of 120 the shaft 17 of the upper feed roll by screws 91 the stems of which pass through arcuate slots 93 in the disk and are threaded into the bearing. It is thus possible to adjust the disk angularly and by changing the 125 angular inclination of the slot 89, to determine the extent of angular movement which is imparted to the splitting knife 15 by a given extent of bodily movement of the upper feed roll.

Hitherto in machines of this general type, in which a pair of feed rolls and an angularly movable knife have been employed, the extent of angular movement permitted to the knife has been comparatively small owing to the fact that it was necessary to have the edge of the knife close to the bite of the rolls and any considerable angular movement of the knife would cause it to contact with one of the rolls. If, on the other hand, the knife were located at a sufficient distance from the bite of the rolls to permit extended angular movement, then the stock would buckle more or less between the point engaged by the rolls and the point engaged by the knife. In the present machine the difficulties outlined above have been overcome. The feed rolls are formed with a series of parallel grooves 95 into which extend suitably shaped projections on pressers 97, 99 which extend rearwardly of the bite of the rolls into close proximity to the edge of the knife. The rear ends of the pressers are vertical and consequently the knife may be tilted to any desired angle. The presser 97 is provided with a stem which passes up through a bore in the bearing of the upper roll and is urged downwardly at all times by a spring 103, the limit of its downward movement being determined by the position of a nut 105 threaded on the stem. A lock nut 107 holds the nut 105 from becoming displaced. The mounting of the lower presser 99 is similar to that of the presser 97 and will not be described in detail.

With the construction thus far described, the feeding of the stock would cease when the rear end of the stock had passed the bite of the feed rolls. In other words, the rear end of the stock for a length approximately equal to the distance from the bite of the feed rolls to the edge of the knife would not be fed to the knife. In order to provide for feeding the last portion of the stock to the knife, a pusher 109 is provided at one end of an arm, the other end of which has a strap 111 arranged to encircle an eccentric 113 fast to the shaft 27 which is driven by means of a gear 115 from the gear 37. The pusher extends up through a slot in the table 121 and is supported adjacent the feed rolls on the upper end of a rod 117 which is urged upwardly into the position shown by spring 119 but may yield in opposition to the force of the spring. Normally the pusher occupies the position shown with its upper side in contact with the lower side of the presser 97. When, however, a piece of stock is placed upon the table 121 and presented to the feed rolls, the pusher is forced down and continues to reciprocate beneath the stock until the rear end of the stock is close to the bite of the feed rolls. At this time, on one of its back strokes, it rises, en-

gages the end of the stock and feeds the last portion of the stock to the knife, the driving mechanism of the pusher being constructed to cause it to impart the same rate of feed to the stock as do the feed rolls. 70

The edge gage 73 (see Fig. 1) has a slotted tail through which passes the stem of a screw bolt 123 by which it is adjustably held in position. As thus far described, and as shown in the drawings, the position of this 75 gage is such that the axis about which the splitting knife is angularly movable is located midway between the operative face of the gage and the edge of the stripping knife. When this gage is adjusted into a different 80 position so as to cause the stripping knife to cut off a narrower or a wider strip, the axis of movement of the splitting knife will no longer coincide exactly with the center line of the strip. In such case the axis of 85 the splitting knife will be above or below and to the right or left of the center of the strip. The purpose of the vertical adjustment of the knife holder carrier 67 is to provide for such cases; and although this 90 adjustment will not cause the axis to coincide exactly with the center of a narrower or a wider strip, it will serve practically for most purposes, since the strips do not vary greatly in width. 95

Although the invention has been set forth as embodied in a particular machine, it should be understood that the invention is not limited in the scope of its application to the particular machine which has been 100 shown and described.

Having thus described the invention, what is claimed as new and desired to be secured by Letters Patent is:

1. A machine of the class described, having, in combination, a pair of members for engaging a piece of stock on both sides to feed it, means for causing said members to move equally toward and from each other in accordance with a dimension of the stock 110 at the point engaged, a movable knife, and means responsive to the extent of separation of the feed members for determining the position of the knife. 105

2. A machine of the class described, having, in combination, a pair of members for engaging a piece of stock on both sides to feed it, means for causing said members to move equally toward and from each other in accordance with a dimension of the stock 115 at the point engaged, an angularly movable knife, and means responsive to the extent of separation of the feed members for determining the position of the knife. 120

3. A machine of the class described, having, in combination, a pair of separable rolls for feeding a piece of stock, means for rotating said rolls, connecting means between the rolls constructed and arranged to compel them, when separated or caused to ap- 125

- proach, to move equally in opposite directions, a knife, and connecting means between the knife and one of the rolls for automatically varying the inclination of the knife in accordance with the extent of separation of the rolls.
4. A machine of the class described, having, in combination, a pair of separable rolls for feeding a piece of stock, means for rotating said rolls, connecting means between the rolls constructed and arranged to compel them, when separated or caused to approach, to move equally in opposite directions, a knife, and means responsive to the thickness of the stock being operated upon for varying the inclination of the knife.
5. A machine of the class described, having, in combination, a pair of rolls separable to provide for variations in the thickness of the stock, means for rotating the rolls to feed the stock, and an inclined knife arranged to split the stock into two beveled pieces, said knife being angularly movable about an axis which passes approximately through the center of the stock, and means whereby the knife may be raised and lowered to maintain approximately this relative position of the axis and the stock irrespective of variations in the thickness of the stock.
6. A machine of the class described, having, in combination, means for feeding a piece of stock, a knife holder in the form of a cylindrical shell, a knife mounted in the holder, and a carrier in which the holder is adjustable about the axis of the shell.
7. A machine of the class described, having, in combination, means for feeding a piece of stock, a knife holder in the form of a cylindrical shell, a knife mounted in the holder, a carrier in which the holder is adjustable about the axis of the shell, and means whereby the holder may be adjusted.
8. A machine of the class described, having, in combination, means for feeding a piece of stock, a knife arranged to cut the stock on a bevel, means including a lever for varying the inclination of the knife to vary the bevel, a member having a slot therein, a member carried by the lever and extending into the slot, and means whereby the slotted member may be adjusted and thereby the lever and the knife.
9. A machine of the class described, having, in combination, a tool for operating upon a piece of stock, means for feeding the stock to the tool, said tool and feeding means being spaced apart so that the last portion of the stock for an extent equal to the distance between the tool and the feeding means would remain unfed, and auxiliary means becoming operative when this stage is reached to complete the feeding of the stock.
10. A machine of the class described hav-
- ing, in combination, a knife for splitting a piece of stock, a pair of rolls for feeding the stock to the knife, the knife being spaced from the rolls so as to permit extended angular movement of the knife, and auxiliary means for feeding the last portion of the stock from the rolls to the knife.
11. A machine of the class described, having, in combination, means for feeding a piece of stock, a knife spaced from the feeding means, guiding means extending from the feeding means to the knife, and auxiliary feeding means for advancing the last portion of the stock to the knife.
12. A machine of the class described, having, in combination, means for feeding a piece of stock, a knife spaced from the feeding means, guiding means extending from the feeding means to the knife, auxiliary feeding means, and means for causing the auxiliary means to engage the rear end of the stock and complete its feeding movement.
13. A machine of the class described, having, in combination, means for feeding a piece of stock, a knife to which the stock is fed, the knife being spaced from the feeding means, guides arranged to engage the stock as it passes from the feeding means to the knife, an auxiliary feed member, means for operating said auxiliary member, and yielding means for supporting said member.
14. A machine of the class described, having, in combination, a knife, a support for the stock, means for feeding the stock over the support to the knife, an auxiliary feed member, means for continuously operating said member, and yielding means for urging said member into a position in which its operative portion is above the level of the support.
15. A machine of the class described, having, in combination, a knife, a support for the stock, means for feeding the stock over the support to the knife, an auxiliary feed member held beneath the stock until the rear end of the stock passes said member, and means becoming effective thereafter to cause the member to engage the rear end of the stock.
16. A machine of the class described, having, in combination, a pair of members for engaging a piece of stock, means for causing said members to move equally toward and from each other in accordance with a dimension of the stock at the locality engaged, a movable knife, and means responsive to the extent of separation of the members for determining the position of the knife.
17. A machine of the class described, having, in combination, a pair of members for engaging a piece of stock, means for causing said members to move equally toward and from each other in accordance with a dimension of the stock at the locality engaged,

an angularly movable knife, and connecting means between the knife and one of the members for automatically varying the inclination of the knife in accordance with the extent of separation of the members.

18. A machine of the class described, having, in combination, a tool for operating upon a piece of stock, means for feeding the stock to the tool, said tool and feeding means being spaced apart, and auxiliary feeding means for feeding the last portion of the stock to the tool.

19. A machine of the class described, hav-

ing, in combination, a tool for operating upon a piece of stock, means for feeding the stock to the tool, a continuously operated auxiliary feed member past which the stock is fed, and means for rendering said member effective when the rear end of the stock has passed it.

In testimony whereof I have signed my name to this specification.
